UNITED STATES PATENT OFFICE.

ORLANDO C. MOORE, OF MORROW, OHIO.

HUSKING-MACHINE.

No. 802,227.

Specification of Letters Patent.

Patented Oct. 17, 1905.

Application filed April 6, 1905. Serial No. 254,098.

To all whom it may concern:

Be it known that I, ORLANDO C. MOORE, a citizen of the United States, and a resident of Morrow, in the county of Warren and State of Ohio, have invented a new and Improved Husking-Machine, of which the following is a full, clear, and exact description.

My invention relates to corn-huskers, it being more particularly directed to the feed mechanism for the snapping-rolls.

In husking-machines if the movable snapping-roll is set with comparatively light tension it may permit smaller ears to pass without removal and is liable to shell off much of the corn. It is therefore desirable to apply considerable pressure, which insures the perfect snapping of the ears; but when this is done it renders automatic feeding practically impossible, since it becomes difficult for the stalks to enter between the snapping-rolls, and they frequently catch and choke the feed. This is fatal to satisfactory operation, which is dependent upon a substantially uniform regular passage of the material between the snapping-rolls. If it were otherwise, it would require the constant attention of an operator to back off the choked feed, or that which failed to enter, and again start it forward.

To obviate these difficulties and to provide a mechanism which will allow the applying of the proper pressure to the snapping-rolls and at the same time secure automatic feed is the principal object of my invention.

Reference is to be had to the accompanying drawings, forming a part of this specification, in which similar characters of reference indicate corresponding parts in all the views.

Figure 1 is a top plan view of the feed end of a husking-machine to which one embodiment of my invention is applied. Fig. 2 is a vertical longitudinal section therethrough on the line 2 2 of Fig. 1. Fig. 3 is a transverse vertical section on the line 3 3 of Fig. 2. Fig. 4 is a detail in side elevation of a portion of the driving-gearing; and Figs. 5 and 6 are enlarged sectional details on the lines 5 5 and 6 6, respectively, of Fig. 2.

Journalized in fixed bearings in a frame 10 is a rotatable drum 11, over which operates a feeding belt or member 12. This is shown as consisting of parallel belts connected by cross-slats and serves to convey the stalks to the husker and assists in effecting their introduction. Above the belt is a companion feeding member in the form of a rotatable grooved roll 13, the journals of which turn in boxes

14 14 capable of vertical movement in ways carried by the frame.

In the frame in advance of the feeding members is journalized a stationary snapping-roll 15 and a bodily-movable companion roll 16. The bearings 17 of this movable roll are mounted in arms 18 18, swinging about the shaft of the drum 11 and being connected to move together by a bar 19. Springs 20 contact with the arms and with the frame and serve to hold the roll 16 in contact with its companion. The pressure of the springs may be adjusted by screws 21, threaded through the upper portion of the frame. Beyond the snapping-rolls the frame carries the usual rotatable shredding-cylinder, (not shown,) to the shaft of which power is applied. It has rotating with it a gear 22, which meshes with a gear 23 upon the shaft of the stationary snapping-roll. This has rotating with it a pinion 24, meshing with an idle pinion 25, which drives a gear 26 upon the shaft of the drum 11. This train of gearing provides for the rotation of the lower snapping-roll and 80 the travel of the feed-belt in the same direction. Upon the opposite end of the drum-shaft is fixed a gear 27, engaging a pinion 28 upon the shaft of the upper snapping-roll to rotate this in the opposite direction from its 85 companion. It should be noted that the mounting of this bodily-movable snapping-roll upon the rigidly-connected arms not only maintains it throughout its length in the proper relation to the lower roll and causes 90 both springs to be uniformly effective, but also permits the pinion 28 to swing about the gear 27 in such a manner that a proper meshing of the teeth will be secured through the entire range of movement of the upper roll. 95 The feed-roll 13 is shown as turned in a direction opposite to the travel of the belt by sprocket-gearing 29, connected with the shaft of the upper snapping-roll.

Each of the arms 18 has beyond the bearing 17 an extension 30, projecting into the lower end of a slot 31 in a link 32. Each of these links depends from the inner end of a lever 33, which has an adjustable fulcrum consisting of a box 34, which may be moved 100 longitudinally of the lever, trunnioned in a bracket 35. Each bracket, as illustrated, is clamped in place by bolts 36, passing through slots 37 in the horizontal members of the frame. It will be seen that the movement of these fulcrum-boxes toward and from the links will vary the strokes of the latter, the

nearer the boxes approaching to the links the shorter their travel. Upon the outer end of each of the levers is shown a roll 38, which contacts with a cam 39, fixed upon a shaft 40, extending transversely of the frame and being rotatable therein. Each of the cams comprises a portion concentric to the axis (designated by 41) and a recess 42 of sufficient size to admit a portion of the periphery of the roll.

10 The shaft 40 is preferably mounted in independently-movable standards 43, which may be secured in place by bolts 44, extending through vertical slots 45. This permits the cam-shaft to be adjusted toward and from the rolls to control the initial positioning of the upper snapping-roll. Fast upon the shaft 40 is an arm 46, which is connected by a rod 47 with an arm 48 upon a transverse shaft 49. This shaft 49 also has at each side of the arm 15 48 an arm 50, from which depends a link 51, which links at their lower ends are articulated to the shaft of the roll 13.

15 20 25 30 35 40 45 50 55 60

The material being placed upon the conveyer-belt is advanced by it to the vertically-movable feeding-roll, which is raised, and through the intermediate arms and connecting-rod rotates the cam-shaft. The rolls of the levers 33 normally lie in the cam-recesses, and at this time the snapping-rolls are in contact, the ends of their carrier-arms being at the bottoms of the slots in the links 32. As the cam-shaft is rotated the lever-rolls immediately ride out of the recesses and through this lever-and-link system raise the upper snapping-roll from its companion a sufficient distance to give the proper gripping angle. This occurs just at the moment that the ends of the stalks are presented to the snapping-rolls, which therefore readily enter between them and are operated upon. After the lever-rolls have once left the recesses they are upon the concentric portions of the cams, so that the automatic separation of the snapping-rolls is not increased no matter how large quantities of the material pass between them. It should be noted that at all times the snapping-roll springs are capable of exerting their full pressure and that the movement of the upper roll is not interfered with, the extensions of its supporting-arms being free to rise through the slots in the links 32. If the character of the material fed is such that it is desirable to secure a greater or less initial separation of the snapping-rolls, the operator has only to move the lever-fulcrums toward or from the rolls, thus varying the effective throw. This arrangement allows the use of such spring-pressure upon the upper snapping-roll that certain action may be secured, since the automatic separation obviates any possibility of a failure of the material fed to be properly engaged.

Having thus described my invention, I claim as new and desire to secure by Letters Patent—

1. In a husking-machine, the combination 65 with rotatable feeding members movable toward and from one another, of separable snapping-rolls, and means whereby the snapping-rolls are separated upon the movement of the feeding members.

2. In a husking-machine, the combination 70 with rotatable feeding members movable toward and from one another, of separable snapping-rolls, and connections between the feeding members and snapping-rolls operating to 75 separate said snapping-rolls upon the separating movement of the feeding members.

3. In a husking-machine, the combination 80 with movable feeding members, of rotatable snapping-rolls, one of which is bodily movable, a lever system connected with the bodily-movable roll, and a cam rotatable by the movement of a feeding member and coöperating with the lever system.

4. In a husking-machine, the combination 85 with movable feeding members, of rotatable snapping-rolls, one of which is bodily movable, a lever system connected with the bodily-movable roll, a cam rotatable by the movement of a feeding member and coöperating 90 with the lever system, and means for permitting the snapping-roll to move independently of the lever system.

5. In a husking-machine, the combination 95 with movable feeding members, of rotatable snapping-rolls, one of which is bodily movable, a lever system connected with the bodily-movable roll and having an adjustable fulcrum, and a cam rotatable by the movement of a feeding member and coöperating 100 with the lever system.

6. In a husking-machine, the combination 105 with a frame, of a snapping-roll rotatable upon the frame, a pair of swinging arms connected to move together, links having slots to receive the arms, levers to which the links are connected, cams coöperating with the levers, a movable feed member, and means for rotating the cams upon movement of the feed member.

7. In a husking-machine, the combination 110 with a frame, of a snapping-roll rotatable upon the frame, a pair of swinging arms connected to move together, links having slots to receive the arms, levers to which the links are connected, adjustable fulcrums for the levers, cams coöperating with the levers, a movable feed member, and means for rotating the cams upon movement of the feed member.

115 120 In testimony whereof I have signed my name to this specification in the presence of two subscribing witnesses.
